CLAIM

The ornamental design for a charging stand with removable base plate, as shown and described.

DESCRIPTION

FIG. 1 is a top front perspective view of the present charging stand with removable base plate;

FIG. 2 is a left side view of the charging stand with removable base plate of FIG. 1;

FIG. 3 is a right side view of the present charging stand with removable base plate;

FIG. 4 is a front view of the present charging stand with removable base plate;

FIG. 5 is a rear view of the charging stand with removable base plate of FIG. 1;

FIG. 6 is a top view of the charging stand with removable base plate of FIG. 1;

FIG. 7 is a bottom view of the charging stand with removable base plate of FIG. 1; and,

FIG. 8 is a top rear perspective of the charging stand with removable base plate of FIG. 1.

The broken lines in the drawings depict portions of the charging stand with removable base plate that form no part of the claimed design.

1 Claim, 6 Drawing Sheets
